UNITED STATES PATENT OFFICE

EDMUND MORRIS, OF GRAND RAPIDS, MICHIGAN, ASSIGNOR TO GRAND RAPIDS STORE EQUIPMENT CORPORATION, OF GRAND RAPIDS, MICHIGAN, A CORPORATION OF MICHIGAN

PARTITION HOLDER FOR COUNTERS

Application filed May 31, 1928. Serial No. 281,798.

This invention relates to holders for glass partitions used above the top of a counter, table or the like in dividing the counter space into a plurality of merchandise receiving bins or compartments.

In constructions of this character vertical border members are located around and secured to the side and end edges of the counter or table top and the space surrounded by said border members is first divided by the plurality of parallel vertical partitions of glass, usually extending between the side border members while between the adjacent glass partitions, or between the end partitions and the end border members shorter lengths of glass are used to divide the cross compartments into compartments or bins of shorter length.

The present invention is concerned with a very simple novel and practical device for holding the vertical glass partitions disposed above the counter or table top between the side border members. It is an object and purpose of the present invention to provide a device of this character which may be adjusted to any desired position and which, when the glass partition is applied between any two of the same located at opposite sides of the counter, is automatically locked or gripped in position and at the same time automatically exerts considerable pressure against the ends of the glass partitions so as to hold them from looseness or rattling. In fact, any movement of the partitions except a movement upwardly to remove the partitions entirely from the counter top is precluded.

An understanding of the invention for the attainment of these ends may be had from the following description taken in connection with the accompanying drawing, in which,

Fig. 1 is a fragmentary perspective view illustrating one corner of a counter or table top with a side and end border member and showing how one of the vertical glass partition members is removably and adjustably yet securely held in place at its end.

Fig. 2 is a fragmentary vertical section through the top and a side border member illustrating the partition holder in side ele-

vation previous to the application of a partition thereto, and

Fig. 3 is a perspective view of one of the holders of my invention.

Like reference characters refer to like parts in the different figures of the drawing.

The counter or table top 1 may be of any conventional construction, usually rectangular in outline, to the side edges of which side border members 2 are secured. Similar end border members 3 are secured at the end edges of the top. The means by which the border members 2 and 3 are secured to the top is no part of the present invention. A distance below the upper edge of each of the border members and at the inner side thereof a downwardly and outwardly continuous groove 4 is made located at an acute angle to the vertical plane of the inner side of the border member in which it is made.

The holder for the ends of partitions, where they come against either the side or end border members, is made of sheet metal. At its upper end it has a relatively wide flat section 5 located substantially in a vertical plane, continuous with which is a narrower downwardly extending web 6 forming the web of a channel guide and retainer which is completed by side flanges 7 turned at right angles from the edges of the web 6 as shown in Figs 1 and 3. At the upper edge of the section 5 a lip 8 having a length equal to the width of the section 5 and a width slightly less than the depth of the slot or groove 4 in the border member is provided by turning the metal outwardly and downwardly at an angle to the section 5 somewhat less than a right angle. At each end of the lip 8 short tongues 9 are turned upwardly, the same being of the height shown at the edge of the lip 8 and tapered downwardly to a point at the bend or angle 10 between the lip and the section 5.

Any desired number of the sheet metal holders may be applied to the opposite side border members 2 with the members 8 and the tongues 9 thereon inserted into the groove 4, the width of the groove 4 being sufficient that the tongues 9 may be inserted therein. When inserted in this manner and

before any partitions are applied thereto the upper section 5 with the channel portion below it is located substantially as shown in Fig. 2, that is, in a plane located at an angle to the vertical plane of the inner side of the border member 2.

A pair of the holders, one at each side of the top carried between opposite side border members 2, may be properly located and a 10 partition 11, which is usually of glass, though it may be of any other material, is forced vertically downward into the channel guides provided by the webs 6 and flanges 7.

When this occurs the channel guides together with the upper section 5 are forced into substantial contact with the inner sides of the border members 2, the metal partition holding member bending or springing at the bend; and it is also evident that the tongues 9 are forced upwardly against the upper sides of the grooves 4 in which they are located; engaging very snugly therewith if not actually indenting or pressing thereinto.

It is evident that as many pairs of the partition holding members may be used as desired to divide the space above the counter top into a plurality of elongated compartments extending across the table. When a partition has been forced downwardly between a pair of the holding members it is securely and snugly held in place. The holding members can not shift position respecting the border members on which they are mounted, while the tendency of the holding members to spring back to the position shown in Fig. 2 causes pressure to be exerted on the ends of the partitions 11 holding them snugly and eliminating any possibility of looseness or rattling. It is also evident that if desired a partition may be shifted to a different position by merely lifting the same in an upward direction to disengage from the holders whereupon the holders may be shifted and the partitions again inserted in place.

The construction of holder described is also available for use on the end border members 3 to hold the ends of other short partitions located at right angles to and between the border members 3 and the adjacent glass cross partitions 11. The ends which contact with the partitions 11 will be engaged therewith by use of a different structure which is no part of the present invention but which will be the subject matter of a co-pending application, but those ends of the shorter partition which lie adjacent the border members 3 will be held in the same manner as the ends of the partitions 11 as herein described.

The construction described is very practical and simple, durable in service and especially effective in operation. The invention is defined in the appended claims and is to

be considered comprehensive of all forms of structure coming within their scope.

I claim:

1. In combination with a top for a counter, table or the like, vertical border members around said top, each having a groove at its inner side cut at an angle to the vertical, sheet metal members located in the grooves of opposite border members each having a guiding channel portion, and vertical partitions extending between said opposite border members having their ends slidably received in channel portions of the sheet metal members. 70

2. In combination with a top for a table, 80 counter or the like, border members extended upwardly from opposite edges of the table, each of said border members having a groove at its inner side, metal members each having a lip at one end received in the 85 grooves of opposite border members, and having guiding portions of channel cross section extending from said lip and vertical partitions disposed across the table top between said border members with their ends 90 located in the channel portions of the metal members. 90

3. A construction containing the elements in combination defined in claim 2, said metal members when attached to the border members normally having their guiding portions 95 extending at an angle to the vertical whereby the same are forced toward the inner sides of the border member on applying the partitions thereto, and said lips within the 100 grooves are pressed against sides of said grooves. 100

4. A device for receiving and guiding the end of a vertical partition comprising, a vertical section of sheet metal having a narrow portion at one end, flanges bent at right angles in one direction from the narrower portion of said section and a lip bent from the wider portion of said section in the opposite direction, said flanges beginning adjacent the lip and gradually tapering to 105 their full height. 110

5. A construction containing the elements in combination defined in claim 4, said lip at each end thereof being formed with projecting tongues. 115

6. In combination with a top for a table, counter or the like, of a vertical border member attached at one edge of the top and extending above the same having a groove at its inner side, and a member of metal having a substantially vertical section wider at one end than at the other, substantially parallel flanges extending at right angles from the edges of the narrower portion of said section, a lip extending in the opposite direction from the wider portion of said section at an angle thereto, said lip being received in the groove of the border member, and tongues extending from the end of said 120 125 130

lip, said tongues being of greatest height at the free edge of said lip and progressively decreasing in height to the opposite edge of the lip where bent from said vertical section.

5 7. Means for receiving and guiding one end of a vertical partition comprising a vertically positioned channel guide, the web of said guide being widened at one end and the flanges being correspondingly decreased in height, and a lip bent from the edge of said widened portion of the web in a direction opposite to the opening of said channel.

10 8. Means for receiving and guiding one end of a vertical partition comprising a vertically positioned channel guide, and a horizontal lip extending from said guide in a direction opposite to the opening of the channel thereof, said lip being wider than the web of the channel guide.

15 20 In testimony whereof I affix my signature.
EDMUND MORRIS.
